UNITED STATES PATENT OFFICE.

ADAM D. GOETZ, OF MARTINSBURG, PENNSYLVANIA.

LEATHER-CUTTING DIE.

SPECIFICATION forming part of Letters Patent No. 392,673, dated November 13, 1888.

Application filed February 23, 1888. Serial No. 264,954. (No model.)

To all whom it may concern:

Be it known that I, ADAM D. GOETZ, a citizen of the United States, residing at Martinsburg, in the county of Blair and State of Pennsylvania, have invented certain new and useful Improvements in Leather-Cutting Dies, of which the following is a specification, reference being had therein to the accompanying drawings.

10 This invention has relation to cutters for forming from a piece of leather at one operation thongs, whangs, shoe-strings, &c.; and among the objects in view are to provide such a device with a convenient and suitable head, said head to be cast integral with the die or cutter, whereby the operation of cutting is facilitated.

15 Other objects and advantages of the invention will hereinafter appear, and the novel features thereof will be particularly pointed out in the claims.

Referring to the drawings, Figure 1 is a bottom plan view of a leather cutter or die constructed in accordance with my invention. Fig. 2 is a central vertical section on the line 25 *xx* of Fig. 1.

Like letters indicate like parts in both figures of the drawings.

20 A represents the die or cutter, which is formed of a strip of steel sharpened at one edge and of a convolute form.

B represents the head in which the die is seated, each convolution of said die being spaced by the metal forming said head. Formed integral with the head B, or it may be secured 35 thereon, is the handle B', having in its upper end a recess, B'', in which is driven a block, preferably of wood, B', upon which is mounted one or more layers of leather, B'', secured to the block by means of a screw, B'', passing through 40 the leather and into the block.

In practicing my invention a strip of steel, A, of the required width, is ground throughout its length, as at A', after which a strip, preferably of leather, of a thickness in accordance 45 with the thong to be cut and of a width half the width of the strip A, is laid on said steel

strip and the two preferably wound tightly around a mandrel. A wire band is then secured around the cutter as thus far formed, and the strap or strip of leather pressed down 50 flush or even with the dull side of the cutter. The cutting-face is now filled with core-sand and baked until sufficiently hard, when the leather strap is removed, and the cutter as thus far formed is placed in a suitable flask conforming in shape to the head and handle desired. The brass or other metal of which the head and handle are to be formed is then poured 55 in a melted state into the flask, which thus fills the spaces between the convolutions of the strip A not occupied by the sand. After the metal has cooled the flask is removed and the sand picked from the face of the die.

As thus described it will be seen that an exceedingly cheap, strong, and durable leather-cutting die is provided, and that no extraneous means are employed for maintaining the convolutions of the die in their proper relative positions and in connection with the head and handle.

70 Other than convolute forms of dies may be made in this manner, in which case the mandrel may be changed or its use obviated.

Having described my invention, what I claim is—

75 1. The die herein described having an integral head formed with a handle provided with a recess at its top, and a cushioning device mounted in said recess, substantially as specified.

80 2. A die for the purpose specified, consisting of a convolute strip of metal, in combination with a metal head cast thereon, the metal of the head taking into and forming the spaces between the convolutions of said strip, substantially as specified.

85 In testimony whereof I affix my signature in presence of two witnesses.

ADAM D. GOETZ.
